United States Patent Office.

WELLINGTON DENISON, OF ROME, NEW YORK, ASSIGNOR TO HIMSELF AND JOSEPH H. KNIGHT, OF SAME PLACE.

Design No. 4,747, dated April 4, 1871.

DESIGN FOR GANG-PRESSES.

The Schedule referred to in these Letters Patent and making part of the same.

To all whom it may concern:

Be it known that I, WELLINGTON DENISON, of the city of Rome, in the county of Oneida and State of New York, have invented a new, original, and useful Design for a Gang-Press, of which the following is a specification.

Nature and Objects of my Invention.

My invention consists of two or more presses, as shown, attached together by appropriate means, and forming a gang-press, by which the pressing of cheese, tobacco, hops, and the like, in large quantities at once, can be accomplished in a very small compass and with great facility and expedition, the object of my invention being to economize and utilize space and labor.

The accompanying photographs are perspective views of the side and end of my design for a gang-press.

General Description.

In the above-mentioned photographs—

A A are the head-blocks forming the ends of the gang-press, and constituting its main supports.

B B B, &c., are parallel rods, made of wood or metal, or both, extended between the front head-block and the rear head-block.

The ends of said rods extend through said head-blocks, and are secured in place by a shoulder upon said rod on the inside of the head-block, and a washer and nut, M, on the outside of said block. These rods are in sets of two, parallel to each other and in the same horizontal plane, and are a sufficient distance apart to support the cheese-hoops or bales in position for pressing. These rods form part of the

frame-work of the press. Their main use is to guide the followers.

D D D are followers. In all of the single presses except the topmost one, the follower slides on four of said rods B B B B, one of said rods supporting and guiding a corner of the follower.

In the topmost press the follower slides on three rods, one at each lower corner, and one at the middle of the upper edge of said follower.

H H H, &c., are the screws, screwing into the front head-block, and serving, when turned, to press up the followers D D D D against the hoops or bales.

K K K K are the levers which turn the screws.

C is a movable head-block sliding upon the rods B B B in the same manner as the followers. Block C is placed at any desired distance along the rods B B B B, &c., by means of cross-rods passed through holes in the rods B B in the same horizontal plane, the holes being made in the rods at desired distances from each other.

The single presses are in general made upon the plan of the Fraser press.

In the present design are three presses placed one over the other, but I do not limit myself to that particular number. I claim the right under my design to make two or more Fraser presses in the combination substantially as shown for a gang-press.

Claim.

I claim—

The design for a gang-press, as shown and described.

Witnesses: WELLINGTON DENISON.
